TO FRANK M. ASHLEY, OF BROOKLYN, NEW YORK, AND ONE-FOURTH TO DICKSON
Q. BROWN, OF NEW YORK, N. Y.

CONTROLLING DEVICE FOR INTERNAL-COMBUSTION ENGINES.

1,073,051.

Specification of Letters Patent.

Patented Sept. 9, 1913.

Application filed November 23, 1912. Serial No. 733,032.

To all whom it may concern:

- Be it known that I, EDWARD DWIGHT KENDALL, a citizen of the United States, and a resident of Elizabeth, in the county of Union and State of New Jersey, have invented certain new and useful Improvements in Controlling Devices for Internal-Combustion Engines, of which the following is a specification.
- 10 This invention relates to thermally controlled adjusting devices, particularly to devices of this character for adjusting the element which controls the admission of fuel in internal combustion engines.
- 15 It has been found in internal combustion engines that after the engine is started using a light volatile combustible liquid such as gasolene as fuel, and has become heated up, it is possible to continue to run the engine
- 20 on a heavier liquid fuel such as kerosene, heavy naphtha, crude oil, etc. This liquid is vaporized in a suitable manner as by being passed through a tube exposed to the heat of the gases of combustion and after
- 25 being so vaporized it may be used in exactly the same manner as the more volatile liquid such as gasolene on which the engine has been started.

Various thermally controlled electrical devices have been hitherto devised for turning off the gasolene and turning on the heavier oil when the engine has become sufficiently heated up. Such devices have the drawback of requiring delicate adjustment, as they depend in their action upon the expansion of a metal or the difference of the rate of expansion in different metals. Moreover, electrical devices involve the employment of a source of current which is often unreliable as the battery may become run down or polarized or injured, the conductors may become broken or disconnected from the jarring of the motor or vehicle, the contacts may become soiled and any one of the comparatively large number of links constituting the chain of the electric circuit may become disabled with the resulting failure of the control.

In the present invention, thermally controlled means are used for directly controlling without intervention of electrical means the mechanical connection between an actuating member which may be driven from the engine itself, and an adjusting ele-

ment which adjusts the position of the part controlling the admission of the fuel.

In carrying out the invention, I connect in any suitable manner to a moving part of the engine, a wheel which is frictionally attached to a shaft extending into a receptacle which is located in a position to be directly affected by the gases of combustion of the engine. This shaft has projections immersed in a mass of easily fusible metal with which the receptacle is filled. When the engine is cold, the metal is congealed or frozen and the shaft is positively coupled to the receptacle, so that when the engine is first started, this receptacle is given a partial rotation until a projection extending therefrom hits a stop. The wheel may then continue to rotate loose upon the shaft while the receptacle is maintained in its adjusted position. When the engine has become sufficiently heated up, the fusible metal is melted, uncoupling the receptacle from the shaft, and a spring then returns the receptacle to its original position. This movement or adjustment of the receptacle may be used to actuate the valve which controls the admission of fuel to the cylinder, so that when the engine is first started, the more volatile liquid will be turned on and after it has become heated up, the heavier oil will be substituted instead.

85
In the accompanying drawing illustrating the invention Figure 1 is a vertical section through a preferred embodiment of the present invention. Fig. 2 is a diagrammatic plan view illustrating the connection of the part which is directly actuated by the shaft to the controlling valve. Fig. 3 is a sectional view illustrating the three-way controlling valve for admitting either gasolene or a heavier oil. Fig. 4 is a section on line 4—4 of Fig. 1.

The actuating element which is connected to a moving part of the engine may be conveniently a wheel 1 which is frictionally connected as by a frictional coupling 2 to a shaft 3 which is suitably journaled and extends into a receptacle 4. The latter is disposed with reference to the engine so as to be subjected to the action of the gases of combustion. It may be located in the manifold exhaust or in a chamber which communicates with the cylinder, so as to allow the gases of combustion to pass there-

in. This receptacle 4 is filled with an easily fusible metal 5 in which extend projections 6 connected to the shaft. These projections are preferably in the form of a fork, but it will be clear that any other form of projection or projections may be adopted provided that they extend into the fusible metal.

When the engine is first started cold, the 10 congealed metal in the receptacle couples the latter with the shaft and thus when the shaft is rotated by the wheel 1, it turns the receptacle along with it and also a sleeve 7 extending from the receptacle and mounted 15 loose upon the shaft. This sleeve has projecting therefrom an arm 8 which is free to move between stops 9 and 10. When the arm 8 strikes the stop 9, the sleeve and shaft are arrested and the wheel continues to rotate 20 idly on the shaft, the relative movement being permitted by the frictional coupling 2. The movement of this arm is transmitted to the valve adjusting element through any desired means, as a forked arm 25 11, having connected therewith a sector 12 which meshes with a larger sector 13 connected with the valve arm 15 through a rod 14.

When the engine has become warmed up 30 sufficiently to melt the fusible metal, the receptacle 4 becomes uncoupled from the shaft, thus freeing the same therefrom and permitting the same to be rotated backward from its position of adjustment for admitting 35 gasoline to the engine to a position in which a heavier oil is admitted to the engine. This backward rotation is accomplished by a spring 16 which is fastened at one end 17 to a stationary part of the framework 40 and at the other end 18 to the sleeve 7. The spring may be disposed in any desired position—as illustrated, the same is located in a recess 19 formed in the framework.

The controlling valve may conveniently 45 consist of a plug 20 having a transverse duct 21 which registers at one end alternately with the ducts 22 and 23 which are connected to the gasoline and oil pipes respectively. At the opposite end, the duct 21 50 registers with a duct 24 connecting with the engine. At the latter end of the duct 21, it is enlarged as at 25, so that it may always open into the duct 24 whether it be adjusted to register with the gasoline or the oil duct. 55 To increase the radiating surface of the walls of the chamber 4, I have preferably constructed this chamber in annular form of sufficient width to permit movement of the projection 6, and I further corrugate 60 the walls as clearly illustrated in Fig. 4.

It will be seen that I have provided a thermally controlled adjusting device which is simple in construction and certain in operation without the intervention of electrical means and its accompanying disadvan-

tages. The thermally controlled means does not depend for its operation upon the expansion of metal requiring delicate adjustment and operates with certainty without any special care or attention on the part of the operator.

Although I have shown the thermally controlled adjusting device applied particularly for adjusting the valve which controls the admission of fuel in an internal combustion engine, it will be understood that any other adjustment on the engine might be made through such means, as for instance, the spark or throttle adjustment. The invention is also applicable in any other relation aside from that of engine regulation where it is desired to make an adjustment which is controlled by the heat which a body may contain.

Various modifications within the scope 85 of the accompanying claims will occur to those skilled in the art and parts of the improvements may be obviously used without the others.

Having thus described my invention, I 90 claim

1. In a device of the character described, a continuously movable actuating member, a regulating element, and thermally controlled means for controlling the operative 95 connection between the actuating member and the regulating element.

2. In a device of the character described, an actuating member, a regulating element, and a yielding connection and a separate 100 thermally controlled connection between the actuating member and the regulating element.

3. In a device of the character described, an actuating member, a regulating element, 105 and a yielding connection and a separate thermally controlled connection between the actuating member and the regulating element, and means for moving the regulating element relative to the actuating element.

4. In a device of the character described, an actuating member, a regulating element, a thermally controlled coupling and a yielding 110 connection between the actuating member and the regulating element, and stops for limiting the movement of the regulating element.

5. In combination, a regulating element, an actuating member, a receptacle, a fusible metallic substance in the receptacle, and 115 means connected to said actuating member extending within the receptacle into the fusible substance, the physical state of the latter controlling the operative connection between the actuating member and the regulating element.

6. In combination, a regulating element, a shaft, an actuating member mounted thereon, a receptacle, a fusible substance in 120 said receptacle, a projection from the shaft 125

- extending into the fusible substance, the physical state of the latter controlling the operative connection between the actuating member and the regulating element. 65
5. 7. In combination, a regulating element, an actuating member, a receptacle, a fusible metallic substance in the receptacle, means connected to said actuating member extending within the receptacle into the fusible substance, the physical state of the latter controlling the operative connection between the actuating member and the regulating element, and means for operating the regulating element when disconnected from the actuating member. 70
10. 8. In combination, a regulating element, an actuating member, a receptacle, a fusible metallic substance in the receptacle, means connected to said actuating member extending within the receptacle into the fusible substance, the physical state of the latter controlling the operative connection between the actuating member and the regulating element, and a yielding connection between the actuating member and the regulating element. 75
15. 9. In combination, a regulating element, a shaft, an actuating element mounted thereon, a receptacle, a fusible substance in said receptacle, a projection from the shaft extending into the fusible substance, the physical state of the latter controlling the operative connection between the actuating member and the regulating element, and a yielding connection between the actuating member and the regulating element. 80
20. 10. In combination, a regulating element, a shaft, an actuating element mounted thereon, a receptacle, a fusible substance in said receptacle, a projection from the shaft extending into the fusible substance, the physical state of the latter controlling the operative connection between the actuating member and the regulating element, and a frictional connection between the actuating member and shaft. 85
25. 11. In combination, a regulating element, an actuating member, a receptacle, a fusible metallic substance in the receptacle, means connected to said actuating member extending within the receptacle into the fusible substance, the physical state of the latter controlling the operative connection between the actuating member and the regulating element, and a spring for returning the regulating element when disconnected from the actuating member. 90
30. 12. In combination, a shaft, a wheel mounted thereon, a yielding connection between the wheel and shaft, a receptacle, a fusible substance therein, a projection from the shaft extending into said fusible substance, a regulating device, a connection between said receptacle and said regulating device. 95
35. 13. In combination, a shaft, a wheel mounted thereon, a yielding connection between the wheel and shaft, a receptacle, a fusible substance therein, a projection from the shaft extending into said fusible substance, a regulating device, a connection between said receptacle and said regulating device, and means for actuating the receptacle when released from the shaft. 100
40. 14. In combination, a shaft, a wheel mounted thereon, a frictional connection between the wheel and shaft, a receptacle, a fusible substance therein, a projection from the shaft extending into said substance, a sleeve connected to the receptacle and extending over the shaft, an arm extending from the sleeve, and a spring connected to the sleeve for actuating the same when uncoupled from the shaft. 105
45. 15. In combination, a shaft, a wheel mounted thereon, a frictional connection between the wheel and shaft, a receptacle, a fusible substance therein, a projection from the shaft extending into said substance, a sleeve connected to the receptacle and extending over the shaft, an arm extending from the sleeve, a spring connected to the sleeve for actuating the same when uncoupled from the shaft, and stops for limiting the movement of the sleeve. 110
50. 16. In combination, a regulating element, an actuating member, a receptacle, a fusible metallic substance in the receptacle, and means connected to said actuating member extending within the receptacle into the fusible substance, the physical state of the latter controlling the operative connection between the actuating member and the regulating element, the walls of the receptacle being corrugated to increase its radiating surface. 115
55. 17. In combination, a shaft, an actuating element mounted thereon, an annular receptacle, a fusible substance therein, an offset projection from the shaft extending within the receptacle into the fusible substance, a regulating element, the physical state of said substance controlling the connection between the shaft and the regulating element. 120
